ELECTRIC CIRCUIT BREAKER

William D. Boller, Milford, Ohio, Warren D. Berkley, Fort Wayne, Ind., Walter Ernst, Dayton, Ohio, and Edwin W. Landmeier, Covington, Ky., assignors to The Wadsworth Electric Mfg. Co., Covington, Ky., a corporation of Kentucky

Original application June 10, 1948, Serial No. 32,204, now Patent No. 2,618,716, dated November 18, 1952. Divided and this application February 16, 1952, Serial No. 274,246

4 Claims. (Cl. 200—116)

1

This invention relates to circuit breakers, and is concerned primarily with a circuit breaker intended to control the circuits in homes and comparable places.

This application is a division of our United States patent application Serial No. 32,204, which was filed June 10, 1948, for Electric Circuit Breaker, and which is now issued as United States Patent No. 2,618,716, dated November 18, 1952.

At the present time, the electrical installations for homes, business establishments, and other places making use of the current supply that is made available by the electric companies includes one or more circuits, each of which embraces a fuse and sometimes a switch associated therewith. When the circuit is overloaded or a short circuit develops, the fuse burns out in a well-known manner and must be replaced before service can be restored.

The present invention has in view as its foremost objective the provision of a circuit breaker which is intended to replace the fuse and switch heretofore employed in controlling such circuits.

Under practical conditions, a plurality of circuits are ordinarily included in electrical installations of the type with which this invention is concerned and a further object of the invention is the provision of a circuit breaker which is susceptible of being assembled in multiple or gangs with each unit controlling one circuit.

In the known combination units of the type intended to be improved by this invention, it has been the practice to provide a pair of contacts for controlling the circuit. When these contacts are in engagement, the circuit is closed and when they are spaced apart, the circuit is open. Usually one of these contacts is fixed and the other is movable. The present invention has in view as an important object the provision of a circuit breaker of the type indicated in which both of the contacts are movable. This arrangement presents certain definite advantages. It is possible to provide for the movement of one contact into opened or closed position under the influence of a manually operable lever while the other contact is placed under the control of the circuit conditions so as to be moved into opened position under overload or short circuiting conditions. This latter contact may

2

be moved back into circuit closing position under the influence of the manually operable lever.

To the end of keeping the contacting surfaces clean a further object of the invention is the provision of a circuit breaker of the type indicated in which the contacts are separated with a wiping action in contrast to a direct pull apart.

In circuit breakers of the type with which this invention is concerned, the opening of the contacts is placed under the control of a bimetallic thermostat together with a so-called "rupture" magnet that is affected by the current conditions to vary the strength thereof. The bimetallic thermostat is heated by overload conditions and when a predetermined condition is reached opens the contacts, whereas the rupture magnet is affected by a short circuit or other comparable instantaneous condition to immediately open the contacts. It has been the practice to mount the rupture magnet on the thermostat so that it is movable therewith. However, the present invention contemplates the mounting of the rupture magnet in a fixed position in the casing and an armature which cooperates therewith is carried by a latch which controls relative movement of the contacts. This arrangement presents certain advantages not only as to ease of assembly but also in sureness of operation. With this arrangement, the rupture magnet is mounted with no physical connection between it and the bimetallic thermostat.

Still another object of the invention is the provision, in a circuit breaker of the type aforesaid, of a novel assembly of a latch, keeper piece, and rivets which is highly simplified as compared to anything heretofore provided for this purpose.

Various other more detailed objects and advantages of the invention such as arise in carrying out the above noted ideas in a practical embodiment will in part become apparent and in part be hereinafter stated as the description of the invention proceeds.

For a full and more complete understanding of the invention reference may be had to the following description and accompanying drawings wherein:

Figure 1 is a longitudinal vertical section through a second modification with certain parts being shown in elevation and depicting the po-

sition of the contacts and associated elements after rupture by circuit conditions;

Figure 2 is a sectional view similar to Figure 1 of the same modification but developing the normally closed position;

Figure 3 is a top plan view of the circuit breaker shown in Figures 1 and 2.

This casing of the electric switch and circuit breaker is shown in the drawings and is identified by the reference character 115. The casing has a top wall 116 which is formed with a large aperture at 117 which accommodates movement of a lever 118 which carries at its free end an operating member of insulating material such as shown at 119.

Substantially opposite to the opening 117 the bottom wall of the casing which is identified at 120 has an inwardly extending boss 121 formed with a recess 122. The ends of the lever 118 are of a rounded nose construction and are received in this recess which functions as a pivot point for the lever 118.

The side wall of the casing is designated 123 and extending inwardly therefrom is a rib 24 formed with a downwardly exposed rounded notch 125 which receives the end of a contact carrier 126 that is of a complementary rounded shape. The contact carrier 126 pivots on its upper end which is received in the recess 125. A tension coil spring 127 has its upper end anchored to the lever 118 as by the pin 128, while its lower end is anchored to the contact carrier 126 as by being received in a slot 129 therein. The spring 127 serves to bias the contact carrier on one side or the other of dead center as determined by the relation of the upper end of the contact carrier 126 with respect to the ends of the spring.

A contact 130 is employed on the lower end of the carrier 126 and a flexible electrical connector 131 connects the carrier with a terminal plate 132 which is anchored in the end wall of the casing. A leaf spring shown at 133 is anchored to the bottom wall 120 as indicated at 134 and functions as an over-travel spring which limits swinging movement of the lever 118. A rocker 135 is pivotally mounted between the side walls of the casing and cover as represented at 136. The lower end of this rocker carries a contact 137 which is adapted to come into abutting engagement with the contact 130 as shown in Figure 2.

Beneath the pivotal point 136 the rocker 135 is formed with a flange 138 that is represented by the dotted lines in Figures 1 and 2. An arm 139 outstands from the lever 118 and at its free end carries a flange 140 which is adapted to engage the flange 138 when the rocker is in the ruptured position depicted in Figure 1. The rocker 135 is also formed with a flange 141 which is adapted to function as a stop in cooperation with a detent member to be later described.

Referring for the moment more particularly to Figure 3 which will be considered in conjunction with the upper part of Figures 1 and 2, it will be noted that the top wall 116 is formed with an opening 142 which may be closed by a slide 144. Immediately adjacent this opening 142 the underface of the top wall 116 is recessed to accommodate slide 144. Extending downwardly from the lower face of this slide is an ear 145 which is connected by a link 146 with the upper end of the rocker 135 as indicated at 147. The slide 144 carries suitable indicia as shown in Figure 3 to indicate when the circuit breaker has been ruptured by a predetermined circuit condition and is to be reset.

At this point it is well to note that the top may also carry suitable indicia which cooperate with the operating member 119 to indicate the position to which the unit has been set.

5 A bimetallic thermostat is represented at 148 and the inner end of this thermostat is secured to an anchoring member 149 which is adjustable through the medium of the screw stem 150 that is appropriately mounted in the end wall of the casing.

10 A latch member 151 comprises a shank of spring construction as illustrated and at its free end carries a detent 152 which cooperates with the stop 141 to hold the rocker 135 against rotational movement when in the position of Figure 2, and a tension coil spring 153 has one end anchored to the rocker 135 below the pivot point 136 as shown at 154 and the other end is immovably secured as represented at 155 to a member 20 which also mounts a magnet 156. The normal tendency of the spring 153 is to urge the rocker 135 in a counter-clockwise direction, speaking with reference to the showing in the drawings.

A coil 157 is wound about the face of the U-shaped magnet 156 and one end of this coil is connected by an electrical connector 158 with a terminal plate 159. The other end is connected by a flexible connector 160 with the thermostat 148 adjacent to its anchorage. Still another flexible connector 161 connects the free end of the thermostat and the rocker 135.

25 A stop for limiting swinging movement of the contact carrier 126 in a counter-clockwise direction is shown at 162. An armature for the magnet 156 is represented at 163 and is pivotally mounted at one end on the structure represented at 155, while at its other end is received in the opening defined by the U-shaped detent 152 of the latch 151.

30 It will be noted that the construction shown in the drawings provides a pivotal mounting of the manual operating lever 118 at the bottom of the casing. The tension spring 127, through which over center forces are applied to the contact carrier 126, is connected at its upper end to the operating lever 118 and at its lower end to the contact carrier 126. The construction provides substantial movement of the spring in response to lever movement, because of the substantial separation of the points of spring attachment with respect to the pivotal axis of the contact carrier, and thereby provides a pronounced snap action effect which is desirable for minimizing arcing when the contacts are disengaged. Also, the tensional force of the spring is borne entirely by the casing at the respective fulcrum notches 125 and 122 which are contained therein. Hence, the effects of wear of the parts are minimized.

60 Operation of the device

Figure 2 depicts the position of the combination switch and circuit breaker when the circuit is closed. This is caused by the engagement of the contacts 130 and 137. It will be noted that the spring 127 being biased at one side of the pivot point 125 continuously urges the contact 130 against the contact 137.

If the switch is to be manually opened the 70 lever 118 is swung to the off position as indicated in Figure 3. As this movement takes place the spring 127 passes dead center, whereupon it biases the contact carrier 126 to rotate the latter in a clockwise direction and move the contact 130 away from the contact 137. This rota-

tive movement of the carrier 126 is limited by the stop at 164. When the switch is to be closed from this off position all that is necessary is to swing the operative member 119 into the on position illustrated, which again causes the spring to pass dead center so that it biases the contact carrier 126 in a counterclockwise direction and brings the contacts into engagement.

Upon the occurrence of a predetermined circuit condition such as a short circuit or an overload, either the armature 163 or the bimetallic thermostat 138 will affect the latch 151 to move the detent 152 downwardly out of the path of the stop 141. The spring 153 will now be effective to move the rocker 135 in a counterclockwise direction and thus the contact 137 away from the contact 130. At the same time through the connection provided by the link 146 the slide 144 is moved to bring the word "reset" beneath the opening 142. This rupture interrupts the circuit and indicates by the slide that the unit will have to be reset to restore the completed circuit.

To accomplish the reset the operator moves the member 118 into the reset position by forcing 118 against over-travel spring 133. This causes a swinging of the lever 118 on the pivot 122. It will be noted from Figure 1 that in the ruptured position the flange 140 on the arm 139 is substantially in engagement with the flange 138. As this movement of the lever 118 takes place the rocker 135 is rotated in a clockwise direction to again bring the contact 137 into engagement with the contact 130 and at the same time moves the stop 141 into effective engagement with the detent 152. It will be noted that when the rocker 135 is swung to the ruptured position any movement of the contact carrier 126 under the influence of the spring 127 is inhibited by the stop 162.

What is claimed is:

1. An electric circuit breaker comprising, a casing having a bottom wall containing a pivot notch, a manually operable lever having a bottom endwise portion pivotally mounted in said notch and having its opposite end extending through the top of said casing, a contact carrier pivotally mounted on said casing at a point between the top and bottom of said lever, and a tension spring extending above and below the pivotal axis of said contact carrier, one end of said spring being connected to said manually operable lever, and the other end to said contact carrier, the said elements being so positioned that the line of force exerted by said spring is shiftable from one side of the pivotal axis of said contact carrier to the other side thereof, for effecting snap action movement of said contact carrier, in response to actuation of said lever, a rocker member pivotally mounted in said casing, the said contact carrier and rocker member having cooperable contacts thereon, means normally restraining the said rocker member against pivotal movement, and means including a latch responsive to circuit overload conditions for effecting operation of said rocker member into contact disengagement position independently of movement of said operating lever.

2. An electric circuit breaker comprising, a casing having a bottom wall containing a pivot notch, a manually operable lever having a bottom endwise portion pivotally mounted in said notch and having its opposite end extending through the top of said casing, a contact carrier pivotally mounted on said casing at a point

between the top and bottom of said lever, and a tension spring extending above and below the pivotal axis of said contact carrier, one end of said spring being connected to said manually operable lever, and the other end to said contact carrier, the said elements being so positioned that the line of force exerted by said spring is shiftable from one side of the pivotal axis of said contact carrier to the other side thereof, for effecting snap action movement of said contact carrier, in response to actuation of said lever, a rocker member pivotally mounted in said casing, the said contact carrier and rocker member having cooperable contacts thereon, means normally restraining the said rocker member against pivotal movement, and means including a latch responsive to circuit overload conditions for effecting operation of said rocker member into contact disengagement position independently of movement of said operating lever, the said casing having a stop member which is engageable by the said contact carrier when the same is in contact engaging position, the said stop member residing closely adjacent the contact on said contact carrier and acting thereby as an arc shield.

3. An electric circuit breaker comprising, a casing having a bottom wall containing a pivot notch, a manually operable lever having a bottom endwise portion pivotally mounted in said notch and having its opposite end extending through the top of said casing, a contact carrier pivotally mounted on said casing at a point between the top and bottom of said lever, and a tension spring extending above and below the pivotal axis of said contact carrier, one end of said spring being connected to said manually operable lever, and the other end to said contact carrier, the said elements being so positioned that the line of force exerted by said spring is shiftable from one side of the pivotal axis of said contact carrier to the other side thereof, for effecting snap action movement of said contact carrier, in response to actuation of said lever, a rocker member pivotally mounted in said casing, the said contact carrier and rocker member having cooperable contacts thereon, means normally restraining the said rocker member against pivotal movement, and means including a latch responsive to circuit overload conditions for effecting operation of said rocker member into contact disengagement position independently of movement of said operating lever, the said casing having a yieldable member mounted therein which is engageable by said contact carrier in its movement away from contact disengagement, whereby the said yieldable member resiliently brings the contact carrier to rest, against the influence of said tension spring, following operation of said lever for effecting contact disengagement.

4. An electric circuit breaker comprising, a casing having a pivot notch formed in a bottom wall thereof and having a slot in the top wall thereof, an operating lever having one endwise portion pivotally journaled in said notch and having the opposite endwise portion extending through said slot and carrying a handle therebeyond, the said casing having a portion providing a second pivot notch extending from a side wall portion thereof at a point intermediate the top and bottom of said casing, a contact carrier having an endwise portion thereof journaled in said second notch and extending in a direction toward said first notch, and a tension spring interconnecting an endwise portion of said contact carrier which is spaced from the second

notch to said lever at a portion thereof which is spaced from the first notch and which is at the opposite side of the pivotal axis of the contact carrier, the said tension spring being shiftable to overcenter positions with respect to the pivotal axis of said carrier in response to pivotal movement of said lever, thereby causing movement of the contact carrier with a snap action, a contact mounted on said carrier, a second contact engageable with the contact on said carrier, and means including a latch for moving the second

contact to engageable and non-engageable positions in response to circuit overload conditions.
